(57) **CLAIM**

The ornamental design for a cabinet, as shown and described.

DESCRIPTION

FIG. 1 is a front perspective view of a cabinet showing the new design;

FIG. 2 is a front view of the cabinet of FIG. 1;

FIG. 3 is a rear view of the cabinet of FIG. 1;

FIG. 4 is a left side view of the cabinet of FIG. 1;

FIG. 5 is a right side view of the cabinet of FIG. 1;

FIG. 6 is a top view of the cabinet of FIG. 1;

FIG. 7 is a bottom view of the cabinet of FIG. 1;

FIG. 8 is a front perspective view of another cabinet of the new design;

FIG. 9 is a front view of the cabinet of FIG. 8;

FIG. 10 is a rear view of the cabinet of FIG. 8;

FIG. 11 is a left side view of the cabinet of FIG. 8;

FIG. 12 is a right side view of the cabinet of FIG. 8;

FIG. 13 is a top view of the cabinet of FIG. 8; and,

FIG. 14 is a bottom view of the cabinet of FIG. 8.

The broken lines shown in the drawings are for illustrative purposes only and form no part of the claimed design.

The two types of dot patterns on the cabinet represent dots and form part of the claimed design.
